TOGGLE FOR HIDE STRETCHERS

Filed April 12, 1929

UNITED STATES PATENT OFFICE

HANS L. JORGENSEN, OF CHICAGO, ILLINOIS, ASSIGNOR TO HARRINGTON & KING PERFORATING COMPANY, OF CHICAGO, ILLINOIS, A CORPORATION OF ILLINOIS

TOGGLE FOR HIDE STRETCHERS

Application filed April 12, 1929. Serial No. 354,530.

This invention pertains to toggles of the type used for stretching hides, skins, etc., on frames during their process of treatment. An object of the invention is to produce a toggle of durable and simplified construction that permits of convenient manipulation by one hand when being applied or removed. Another object is to provide a toggle with an improved form of gripping jaw for firmly securing the hide or skin in stretched position. The invention consists in certain features and elements of construction, herein shown and described, as indicated by the claims.

In the drawings:

Figure 1 is a side elevation of the toggle embodying this invention, shown in open position.

Figure 2 is a front view looking toward the jaws, as indicated at line 2-2 on Figure 1.

Figure 3 is a longitudinal section taken centrally through the toggle, as indicated at line 3-3 on Figure 8; showing the toggle in the closed or gripping position.

Figure 4 is a fragmentary sectional view through the lower jaw.

Figure 5 is a perspective view of the base or frame member.

Figure 6 is a perspective view of the upper jaw.

Figure 7 is a perspective view of the operating lever; and

Figure 8 is a rear end view of the toggle in closed or gripping position.

The toggle embodying the present invention includes a base or frame member, 10, herein shown as a metal stamping formed with laterally spaced upwardly extending sides, 11, the upper ends of which are bent inwardly in a horizontal plane to form shelves or flanges, 12. Pivotally connected to the rear end of the sides, 11, by means of a pin, 13, is an upper jaw, 14, also formed as a metal stamping, composed of two vertical side portions, 15, disposed outside of the frame sides, 11, and connected at the forward end by a transversely extending portion, 16, which serves as the upper jaw proper. Pivotally connected to said upper jaw member, 14, just

rearwardly of the transverse portion, 16, on a transverse pivot, 17, carried by the sides 15, is an operating lever, 18, formed with spaced side walls, 19, dimensioned to fit between the upright walls, 11, of the base, as may be seen in Figures 3 and 8. At their forward ends the sides, 19, having upwardly extending lugs, 21, in which is supported a transverse pivot pin, 22, carrying a roller, 23, which is adapted to coact with the under surface of the horizontal flanges or shelf members, 12, of the base. The outer end of the operating lever is shaped to provide a convenient finger grip in the form of a substantially closed loop or eye, 24.

A lower cooperating jaw member, 25, is positioned between upright sides 11, and is pivotally connected at its forward end to the forward end of the base or frame, 10, in any suitable manner, and as herein shown, by means of trunnions, 26, engaged in the apertures, 27, in the side walls, 11, of said base member. This lower jaw member, 25, when free, extends in an upwardly inclined rearward direction with its narrowed rear portion disposed between the rounded ends, 19^a, of the operating lever side members, 19, and urged toward the transverse pivot, 17, by means of a coil spring, 28, which is interposed between the under side of said jaw member and the base, 10. It will be understood that this spring is maintained in position by any suitable means such as depressions or nodes, struck out of the respective contacting surfaces (not shown). The lower jaw member, 25, is formed with an aperture, 30, through which extends the stud portion, 31, of a removable material-gripping member, 32. Said member, 32, is preferably of circular or button form and has in its upper surface a plurality of concentric, conically-formed corrugations, 33, which coact with the transverse portion, 16, of the upper jaw member for pressing the hide or skin into the corrugations, as indicated in dotted lines at A, thus insuring a firm grip for holding it in stretched position. The stem portion, 31, of the removable member is formed with a peripheral groove, 34, in which the member tends to shift forward due to the inclination

of the jaw, 25, so that the head, 35, may engage the under side of the lower jaw member, 25, as may be seen in Figure 4, and hold said button member, 32, against upward removal. 5 Toggle devices of this general type are ordinarily used in connection with reticulated frames as indicated at B, which may be of wire mesh, perforated plate, etc., and the device is conveniently secured to the frame, B, 10 at any desired opening by means of a hook or spur, 36, formed integrally from the rear edge of the base or frame member, 10, and tapered forwardly and downwardly in a concavo-convex formation. This formation produces a spur of unusual strength adapted to resist the pulling stresses of the hide when stretched, which would tend to shear the hook from its base.

Upon swinging the operating lever, 18, in 20 a downward direction with respect to the position shown in Figure 1, the roller, 23, acts cam-wise against the under side of the flange or shelf members, 12, of the base member, forcing the upper jaw member, 14, in a downward direction about the pivot pin, 13, and during a portion of the range of downward movement of said upper jaw, the pivot pin, 17, engages the tail or rear end portion of the lower jaw, 25, causing it to rock rearwardly, about its trunnions, 26, against the reaction of the spring, 28, so that the jaws are caused to approach a co-operative gripping position, and further movement of the upper jaw (when a hide or skin is interposed 35 between said jaws) will transmit pressure through the thickness of said interposed hide or skin to the button, 32, of the lower jaw, forcing said lower jaw still further in a downward direction. Due to the respective portions of the lever arms of the lower jaw—that is, the relation of the trunnion pivots, 26, to the gripping button and to the tail end, any downward movement of the gripping button is proportionately increased at the tail 40 end of the lower jaw. Accordingly, when said lower jaw is moved by pressure exerted through the hide against the gripping button, the tail end of the lower jaw is moved down out of contact with the pivot pin, 17, (as 45 seen in Figure 3), thus affording a yielding or cushioned gripping action of the jaws; the jaws obtaining the full benefit of the pressure exerted by the spring, 28. It may be understood that with the parts in gripping 50 position the line of direction of the pressure between the roller, 23, and the flanges, 12, will fall between the pivots, 13 and 17, producing an eccentric locking effect, while the pivot pin, 13, will serve as a stop to arrest 55 the lever movement at this locked position.

It will be manifest that the device may be conveniently held in one hand and the operating lever manipulated with the thumb or index finger engaged in the eye, 24, for moving 60 the jaws to closed or open position; and as

soon as the hide or like material is gripped, a horizontal pull may be exerted through the eye of the lever without releasing the grip.

As may be seen in Figure 3, when the jaw portion, 16, and the corrugated button, 32, 70 are in co-operative gripping position, the jaw, 25, is so disposed that the button member is inclined forwardly, in which position only the rear portion of the corrugated surface cooperates with the jaw portion, 16 in which 75 position said rear portion of the button, 32, is disposed substantially parallel to said upper jaw. Thus if certain portions of the corrugations become worn in use, the button may be turned slightly to employ a different 80 part of the corrugated area, or when necessary, a new button may be quickly substituted.

I claim:

1. In a toggle the combination of a base member and cooperating jaw members both 85 pivotally supported on the base with their gripping surfaces normally apart and divergent, operating means reacting between one of the jaw members and the base for swinging the jaw about its pivotal mounting 90 with a part simultaneously engaging the other jaw member and swinging it to bring the gripping areas of the jaws into more nearly parallel relation independently of any gripping pressure between them. 95

2. In a toggle the combination of a base member and cooperating jaw members pivotally supported upon said base member at separate axes, an operating lever and a fulcrum pin by which it is secured to one of the jaw members, means rigidly associated with the base against which said lever reacts for swinging said jaw member toward gripping position, the other jaw member having a part extending adjacent said fulcrum pin, whereby pressure is transmitted from one jaw member to the other for swinging them simultaneously about their respective pivots toward gripping position. 100

3. In the combination defined in claim 2, a 110 spring positioned to react between the base and said other jaw member yieldingly opposing said movement toward gripping position and thus tending to return the parts to open position. 115

4. In a toggle, the combination of a base member, cooperating jaws pivotally supported by said base member and movable about separate axes, and means for forcing the jaws into gripping position, one of said jaws having a removable member provided with a roughened surface, said removable member being of button form, having a plurality of concentric corrugations. 120

5. In a toggle, the combination of a base member, cooperating jaws pivotally supported by said base member and movable about separate axes, and means for forcing the jaws into gripping position, one of said jaws having a removable member provided 125 130

with a roughened surface, the roughened surface of said removable member including a plurality of concentric corrugations arranged in conical relations.

- 5 6. In a toggle, the combination of a base member, cooperating jaws pivotally supported by said base member and movable about separate axes, and means for forcing the jaws into gripping position, one of said 10 jaws having a removable member provided with a roughened surface, said removable member having a stem provided with a circumferential groove, and said jaw having an aperture therein of sufficient size to permit 15 insertion of the stem, whereupon the stem may be shifted to cause a portion of the wall surrounding the aperture to enter the groove.

7. In a toggle the combination of a base member provided with cooperating jaws, one 20 of said jaws being pivotally mounted on the base member, an operating lever pivotally connected to said pivotal jaw intermediate its gripping portion and its pivotal mounting and arranged for co-action with the base 25 member, whereby swinging the lever about its pivot moves said pivotal jaw toward and from the other jaw.

8. In a toggle, the combination of a base member provided with upright sides and a 30 horizontally extending shelf portion supported in spaced relation to the base, cooperating jaws carried by said base member, one of said jaws being pivotally mounted on said base member, and an operating lever 35 pivoted to said pivotal jaw intermediate its gripping portion and its pivotal mounting and having an arm reacting against said shelf portion of the base member, for moving said pivotal jaw toward the other jaw.

- 40 9. In a toggle, the combination of a base member, formed with upright sides, one of which is provided with a laterally extending flange, cooperating jaws carried by the base member, one of said jaws being pivotally 45 mounted on the base, an operating lever pivotally connected to the pivotal jaw and having an outwardly extending arm, and a roller journaled at the end of said arm, co-acting with said flange for moving the pivotal jaw toward the other jaw in gripping 50 position, said roller normally being disposed forwardly of the axis of the lever when the jaws are separated, and adapted to be moved forcibly in the opposite direction beyond said 55 axis for holding said jaws in gripping position.

10. In a toggle, the combination of a base member provided with upright sides, one of which is formed with an inwardly extending 60 flange, cooperating jaws pivotally mounted in said sides of the base member, and an operating lever pivotally connected to one jaw and engageable with the other jaw, said lever having an outwardly extending arm, a roller journaled on the end of the arm, co-acting 65

with the underside of the flange, whereby the movement of the lever in a downward direction causes said jaws to swing about their pivots to gripping position.

11. In a toggle, the combination of a base member provided with upright sides, one of which is formed with an inwardly projecting flange, a main jaw pivotally supported in said sides adjacent one end, and a cooperating jaw pivoted at the opposite end below the main jaw, a spring normally urging the last mentioned jaw in an upward direction, and an operating lever pivotally connected to the main jaw and adapted to engage the upper side of the other jaw, said lever having an arm provided with a roller adapted to co-act with the flange, whereby the swinging of said lever about its pivot urges both of the jaws in a downward direction, against the reaction of the spring, into gripping position. 70 75 80

12. In the combination defined in claim 11, the outer end of said operating lever being formed with a finger grip in the form of a substantially closed loop or eye. 85

13. In a toggle comprising a base and two cooperating jaws both pivoted thereon, a single spring normally urging the jaws toward open position and an operating lever pivotally connected to one jaw, arranged to force said jaw toward the other, said jaws 90 95 being mounted for further movement in opposition to the spring to bring the lever to an eccentrically locked position. 95
